(57) CLAIM

The ornamental design for a jewelry setting, as shown and described.

DESCRIPTION

FIG. 1 is a perspective view of a jewelry setting showing my new design;

FIG. 2 is a perspective view of a jewelry setting showing a second embodiment of my new design;

FIG. 3 is a perspective view of a jewelry setting showing a third embodiment of my new design;

FIG. 4 is a perspective view of a jewelry setting showing a fourth embodiment of my new design; and,

FIG. 5 is a perspective view of a jewelry setting showing a fifth embodiment of my new design.

The broken line showing of either a jewelry setting is for illustrative purposes only and forms no part of the claimed design.
